(57) **CLAIM**

The ornamental design for a case for electronic device, as shown and described.

DESCRIPTION

FIG. 1 is a bottom front perspective view of a case for electronic device showing our new design;

FIG. 2 is a top rear perspective view thereof;

FIG. 3 is a front view thereof;

FIG. 4 is a rear view thereof;

FIG. 5 is a left side perspective view thereof;

FIG. 6 is a right side perspective view thereof;

FIG. 7 is a top front perspective view thereof; and,

FIG. 8 is a bottom front perspective view thereof.

The Figures are illustrated to show contrasting appearance. Areas of the case for electronic device that appear in different shades represent contrasting appearances (e.g., the lighter and darker gray shades shown).
